[57] CLAIM

The ornamental design for an angle gauge, as shown and described.

DESCRIPTION

FIG. 1 is a top, right and rear perspective view of an angle gauge showing my new design;

FIG. 2 is a right elevational view;

FIG. 3 is a rear elevational view;

FIG. 4 is a front elevational view;

FIG. 5 is a top plan view;

FIG. 6 is a bottom plan view; and

FIG. 7 is a top, left and front perspective view of a second embodiment of my new design of FIGS. 1-6. FIGS. 1 and 7 are drawn on a reduced scale.

FIG. 1

FIG. 3

FIG. 4

FIG. 2

FIG. 5

FIG. 6

FIG. 7
